STACKING MECHANISM

Frederick E. Hooper, Marblehead, Mass., assignor
to United Shoe Machinery Corporation, Pater-
son, N. J., a corporation of New Jersey

Application July 27, 1937, Serial No. 155,972

11 Claims. (Cl. 214—6)

This invention relates to mechanism for taking articles from a moving carrier and is herein illustrated as embodied in a mechanism for taking toe tips from the carrier of a machine which operates upon them and piling them in a stack.

In the manufacture of toe tips for shoes, a machine in common use comprises a skiving mechanism, a searing mechanism and a perforating mechanism arranged about the circular path of tip carriers which move around such path from a loading station, where the operator supplies them in succession with toe-tip blanks, past the various mechanisms which operate upon them and back to the loading station.

In order to remove these and other articles from their carriers and to stack the articles, there is provided, in accordance with one feature of the invention, the combination with an article carrier moving in a predetermined path of transferring mechanism for grasping a moving article and removing it from its carrier. In the illustrated construction, the moving carrier has jaws which close upon a toe tip in such a manner as to leave the margin of the tip projecting from the carrier in position to be operated upon by the skiving, searing and perforating mechanisms, said jaws being opened after the last operation; and the transferring mechanism comprises a pair of grippers which are normally held open in position to have the projecting margin of the toe tip carried between them. At the proper moment, the moving carrier throws into operation mechanism for actuating the grippers which causes them to close on the margin of the toe tip, to transfer the toe tip from its carrier to a position above a stack support, to release the toe tip and finally to return to their initial position with the grippers open to receive another toe tip.

In order to press each article down upon the top of a stack, there is provided in accordance with another feature of the invention, pressing means which acts immediately after the article is released to press it into place. In the illustrated construction, two pivoted pressers are provided which are caused to swing down after the grippers have released a toe tip, said swinging down being caused by the moving grippers during the return of the grippers from tip-releasing to tip-receiving position.

These and other features of the invention, including certain details of construction and combinations of parts, will be described as embodied in an illustrated machine and pointed out in the appended claims. Referring now to the accompanying drawings,

Fig. 1 is a plan of a portion of a machine in which the present invention is embodied;

Fig. 2 is an elevation of the transferring and stacking mechanism in process of taking a toe tip from its carrier;

Fig. 3 is a detail, partly in section, showing the lock for the stem of the stack support;

Fig. 4 is an elevation of the grippers and certain parts associated with them as viewed from the right in Fig. 2;

Fig. 5 is a view partly in vertical section and partly in elevation showing, more particularly, the bracket on which the transferring and stacking mechanism and its actuating clutch are mounted and the gearing by which the clutch is driven;

Fig. 6 is a detail, partly in longitudinal section and partly in elevation, showing how the grippers are opened to release the articles;

Fig. 7 is a plan view on an enlarged scale of 20 the transferring and stacking mechanism;

Fig. 8 is a section on the line VIII—VIII of Fig. 7, showing, more particularly, the construction of the clutch, and

Fig. 9 is a detail in rear elevation of the mechanism which releases the grippers and the pressers and throws in the clutch to impart a complete reciprocation to the grippers.

The machine herein shown for operating upon a piece of work is a machine for operating upon toe-tip blanks and is or may be substantially the same as the machine of Letters Patent of the United States No. 1,989,682, granted February 2, 1935, upon application filed in the name of John B. Coffey. In this machine, each toe-tip blank is clamped near its rear margin by the jaws of a tip carrier and, with its margin projecting from the carrier, is fed successively first past a mechanism for skiving its rear edge, then past a mechanism for applying a searing heat along the skived edge and finally past a perforating mechanism for forming a row of ornamental perforations in its margin. In Fig. 1, one end of such a machine is shown. The tip carriers, two of which are indicated at A and B, are adjacent to the perforating mechanism, indicated as a whole at C, and are moving in a circular path in the direction indicated by the arrow. The tip carriers are mounted at the outer ends of stems D and are rotated about an axis which is the center of curvature of the outer edges of the jaws of the carriers. The carrier A is being moved past the perforating mechanism C which is in process of forming a row of ornamental perforations in the rear margin of a toe-tip blank. At 55

the completion of the perforating operation, the jaws of the carrier A will be caused to release their grip upon the finished tip. The jaws 21, 23 are shown in Fig. 2 in their separated relation 5 after the finished tip 100 has been released. The jaw 21 is rigid with the frame of the tip carrier. The jaw 23 is pivoted to the frame of the tip carrier and is held in clamping position against the force of a spring by the levers 25, 27 of a toggle, the toggle being broken after the perforating 10 operation has been completed by contact of the upper end of the lever 27 with a roll 29 which is located in position to engage the lever 27 at the proper time. No further description of the machine will be given, since the details of its construction form no part of the present invention, reference being made to the patent for details 15 not herein shown or described. It will be understood, however, that the tip carriers are rotated 20 in the direction indicated in Fig. 1 by the arrow, and that, after the completion of the perforating operation, the upper jaw of each carrier is swung up to release the tip which it carries, the parts then occupying the positions shown in Fig. 2 with the margin of the released tip 100 projecting beyond the jaws of the carrier into a position 25 in which it may be readily grasped.

As the carriers successively reach the position of the carrier A in Fig. 2, the finished tips are 30 taken from them and stacked. Referring still to Fig. 2, the general operation of the stacking mechanism will be described. A sliding trans- 35 ferrer, indicated as a whole by the letter T, has grippers 31, 33 which are held open at the proper times in their extreme right-hand position to permit the margin of a released toe tip 100 to 40 be carried between them by one of the moving tip carriers. While they are so held, a moving carrier strikes a finger 34, movement of which throws in a one-revolution clutch whereupon the following movements taken place. The grippers close upon the margin of the toe tip. The trans- 45 ferrer T slides to its extreme left-hand position where its grippers 31, 33 are opened (Fig. 6) to release the tip and to permit it to fall upon a spring-supported platform 35 (Fig. 2) which may 50 be pushed down and will remain in any position to which it is pushed. The transerrer then returns to its extreme right-hand position, its grippers being held open to receive another tip; and during this return movement two pivoted 55 pressers 37 are swung down to exert pressure upon the tip which was just deposited upon the platform 35 (or upon the top of the stack of tips 100 which is being built up) and to depress the platform slightly. In this manner, the finished tips are taken successively from the moving carriers and added to the stack.

The transferring and stacking mechanism is 60 mounted upon a bracket 41 (Fig. 5) which is adjustably fastened to the frame of the machine by cap screws 43, said cap screws passing through horizontal slots in the bracket and being threaded into the frame. Turning now to Figs. 65 2 and 3, the platform 35 is fast to the upper end of a hollow tube 45 which is vertically slidable in a second hollow tube 47 having a closed bottom, said tube 47 being held firmly in a split bearing in the bracket 41 by a pinch bolt 49. A slender upright rod 51, the lower end of which is of reduced diameter to fit into a small hole in the bottom of the tube 47, has coiled about it a 70 spring 53, the upper end of which engages a small cylindrical projection on the under side of the platform 35. Freely pivoted on the pinch bolt 75

49 is a detent 55 having a weight 57 at its outer end. The platform 35 is held from turning by means of two stationary vertical rods 58 which pass through notches formed in the left-hand margin of the platform and are provided with pins 59 to limit the upward movement of the platform.

The grippers 31, 33 (Figs. 4 and 6) are pivoted about a stud 61 carried by a block 63 which is 15 slidable on two stationary horizontal rods 65, 10 said grippers being urged at all times to close by torsion springs 67, each of which is coiled about the stud 61 and the ends of which bear against the top of one gripper and the bottom of the other. The grippers are opened at the left-hand 20 end of the sliding movement of the block 63 by reason of an adjustable set screw 69 threaded through a part of the bracket 41 which engages a horizontal stud 72 projecting from one side of the vertical arm of a bell-crank lever 71 pivoted 25 about a stud 73 carried by the block 63, said screw 69 forcing the stud 72 between the inclined tails 131, 133 of the grippers. At the same time that the grippers are opened, the bell-crank lever 71 is swung counterclockwise about its pivot 73, and 30 its horizontal arm rides up the lower rounded face of a catch 75 and is held by the catch so as to maintain the grippers open until said catch is later moved to release the bell-crank lever and permit the spring 67 to close the grippers. 35 The catch 75 is pivoted at 77 to the slide block 63 and is urged at all times by a torsion spring 79 to swing clockwise as far as permitted by a stop pin 81. At its upper end the catch 75 has a tail 175 which, just before the slide block 63 35 starts to move from its extreme right-hand position toward the left, is swung to the left to cause the catch 75 to release the bell-crank lever 71 and thereby permit the closing of the grippers 31, 33 which at that time have received between 40 them the margin of a toe tip.

In order to operate the two pressers 37 during the right-hand movement of the slide block 63 (Figs. 2 and 4), the pivot stud 73 projects from it on each side. Upon the projecting ends of 45 the stud are loosely hung two short arms 83, each carrying at its lower end a roll 85, said rolls being arranged to run respectively on the tops of the two pressers 37. During the left-hand sliding movement of the block 63, when the grippers move from receiving to releasing position, these rolls have no effect upon the pressers. During the right-hand sliding movement of the block 63, when the grippers move back to receiving position, the rolls 85 swing the pressers down. To 50 this end, each arm 83 has an upwardly projecting finger in position to engage, respectively, pins 87 carried by the block 63, said pins being so located as to permit the arms to swing counterclockwise when the rolls 85 on the arms engage the pressers 60 37 during the left-hand movement of the slide 65 block 63 but to prevent the arms from swinging clockwise during the return right-hand sliding movement of the block. Thus, when the slide block 63 moves to the left, the pressers 37 remain in raised position but when the slide block returns, the rolls 85 swing the pressers down.

These pressers are pivoted to the bracket 41 at 89, have tails 137 and are urged at all times by springs 91 to swing upwardly as far as the 70 heads of screw bolts 93 will permit, said bolts being carried by the bracket 41 and extending through slots in the tails 137. If no further provision were made, the pressers 37 would rise 75 into and remain in the position shown in Fig. 2 75

as soon as the rolls 85 ran off from their right-hand ends. In order to hold them down and keep them held down while the slide block 63 finishes its movement to the right and comes to rest with the grippers open, means are provided for locking the pressers in their lowered positions. The tails 137 of the pressers carry rolls, one of which is shown at 95 in Fig. 2, which, when the pressers are swung down, engage catches one of which is shown at 97. Each catch is pivoted at 99 to the bracket 41 and has a tail, to the outer end of which is pivoted at 101 the lower end of an upright link 103 pivoted at its upper end at 105 to the outer end of a link 107, the inner end of which is pivoted at 109 to the bracket. The link 107 has an upwardly extending curved projection to which is pivoted at 111 one end of a slender slide rod 113 which extends through a guiding bore in a lug on the bracket. When the reciprocation of the slide block 63 from its right-hand position is started each time by swinging the finger 34 to throw in the one-revolution clutch, a lug 115 on an arm 129 (Fig. 7) is caused to engage the right-hand end of the rod 113 and push the rod to the left to free the catches 97 from the rolls 95 and permit the springs 91 to swing the pressers up into the position shown in Fig. 2.

The swinging of the finger 34, clockwise as viewed in Figs. 1 and 7, not only throws in the one-revolution clutch in a manner presently to be described and releases the pressers 37 but also trips the catch 75 (Fig. 6) by swinging its tail to the left. Referring now more particularly to Figs. 7 and 9, the hub of the finger 34 is loosely mounted on the upper end of an upright pin 117 rotatably mounted in a bearing in the bracket 41, and is connected by a tension spring 119 to the bracket. Below the point of attachment of the spring to the finger, said finger has a downwardly extending projection through which is threaded a stop screw 121, the end of which is normally held against a part of the bracket 41. The finger 34 thus always remains in the position shown in Fig. 7 except when it is being swung by a moving tip carrier or allowed to swing back after the carrier has passed it. Fastened to the bottom of the pin 117 is an arm 123 connected by a spring 125 with the bracket 41 and by a link 141 with a pivoted dog 143 which is normally held by the spring 125 in contact with a projection 155 on the roller cage of the clutch later to be described. The spring 125, because of the construction just described, also normally maintains the pin 117 in the angular position shown. Adjustably fastened by a pinch screw 127 to the rotary pin 117 is the hub of a second arm 129, the outer end of which lies in the arc of movement of a stud 135 formed on the lower end of a vertical pin 136, the axis of the stud being eccentric to the axis of the pin. The pin is received in a socket formed in the finger 34, the upper end of the pin being of reduced diameter to extend up through a hole in the top of the socket and being threaded to receive a lock nut 139 by which the pin is held in adjusted angular position. When the finger 34 is swung clockwise (Fig. 7) the stud 135 engages the arm 129 and swings it clockwise; and since the arms 129 and 123 are fast to the rotatable pin 117, the arm 123 is also swung clockwise. The arm 129, as it swings clockwise, accomplishes two results. The projection 115 carried by it pushes the slide rod 113 to the left, thus freeing the pressers 37 which thereupon rise; and a face 229 on the arm 129 engages the upwardly extending tail 175 of the catch 75, thus releasing the grippers 31, 33, which then close upon the margin of a toe tip. The arm 123, as it swings clockwise, throws in the one-revolution clutch which imparts a complete reciprocation to the slide block 63. It is, of course, desirable that the grippers 31, 33 be caused to grasp the moving toe tip before the clutch is thrown in, and this timing may be accomplished by varying the angular position of the arm 129 on the pin 117. It is also desirable that the grippers grasp each toe tip midway between the ends of its margin which project from the jaws of a tip carrier; that is, having adjusted the angular position of the arm 129 on the pin 117 so that the grippers grasp the toe tip just before the one-revolution clutch is thrown in, it is desirable to time properly the closing of the grippers with respect to the position occupied at that moment by that one of the moving tip carriers from which a toe tip is to be taken. This is accomplished by varying the angular position of the eccentric stud 135.

Referring now to the one-revolution clutch (Fig. 7), the arm 123 is connected, as has been explained, by a link 141 to a dog 143 pivoted about a stud 149, said dog controlling in the usual manner the operation of a Horton clutch through which one revolution is imparted from a shaft 145 to a disk 146. This disk has threaded into its upper face a screw 148, the stem of which extends through a slot 147 in one end of a lever 150 which is pivoted intermediate its ends about the stud 149, said lever having at its other end a slot to receive the stem of a screw 152 threaded into the block 63. Thus when the disk makes one revolution a complete reciprocation is imparted to the slide block 63 and a finished toe tip is added to the stack and pressed down. The Horton clutch comprises the usual roller cage 151 and rolls 153, said cage being urged at all times to rotate into a position in which the clutch is operative by a spring 154 and having a projection 155 adapted, when engaged by the dog 143, to arrest the rotation of the roller cage and throw out the clutch. The details of construction of the clutch form no part of the present invention and any suitable one-revolution clutch may be employed. The upright shaft 145 is driven (Fig. 5) from a bevel gear 157 on its lower end by a bevel gear 159 on one end of a horizontal shaft 161, said shaft having near its other end a spiral gear 163 driven from a second spiral gear 165 on a horizontal shaft 167 which is a constantly driven shaft of the machine of the patent with its end extended, the extended end of the shaft 167 as well as the end of the shaft 161 being supported in bearings in a bracket 169 which, in turn, is supported by a hanger 171 the upper end of which is hung on a rod 173, which is also a rod of the patented machine with its end extended. A set screw 177 fastens the upper end of the hanger 171 to the extended end of the rod 173.

In the operation of the machine, the arm 129 (Figs. 7 and 9) is adjusted into an angular position such that when the finger 34 is swung by a moving tip carrier the grippers will be caused to close upon a tip, and the pressers will be released just before the clutch is thrown in; and the eccentric stud 135 is adjusted so that the grippers will grasp a toe tip midway between the ends of its margin which projects from a toe-tip carrier. As a toe-tip carrier continues its movement after the toe tip has been perforated, its jaws are 75

opened by contact of the roll 29 with the toggle link 27, and thereafter a portion of the carrier engages the finger 34, swings it clockwise and moves past it. Swinging the finger 34 clockwise causes the eccentric stud 135 to contact with the arm 129 and swing that arm, whereupon the grippers 31, 33 grasp the margin of the toe tip, and the pressers 37 rise. An instant later the one-revolution clutch is thrown in and a complete reciprocation is imparted to the slide block 63 with the grippers 31, 33. During the movement of the grippers from receiving to releasing position, the rolls 85 ride over the pressers 37 without depressing them. At the left-hand end of the movement of the slide block 63, the grippers are opened to release the toe tip above the stack of tips on the support. During the return movement of the grippers to receiving position, the rolls 83 depress the pressers 37 so as to press the released toe tip upon the top of the stack and to push down the stack support, the pressers being locked in lowered position by the catches 97. The slide block 63 continues its movement to the right and comes to rest with the grippers open in position to receive another toe tip from the next toe-tip carrier.

Although the invention has been described as set forth in a particular machine, it should be understood that the invention is not limited to the scope of this application to the particular machine which has been shown and described.

Having described my invention, what I claim as new and desire to secure by Letters Patent of the United States is:

35 1. A machine of the class described having, in combination, an article carrier, means for moving the article carrier in a predetermined path, transferring mechanism past which the carrier moves for grasping a moving article and removing it from the carrier, said mechanism including a pair of grippers which are moved toward each other to grasp an article and are then moved bodily to remove the article, and a normally stationary member which is engaged by the moving carrier as the carrier approaches the transferring mechanism for actuating said mechanism.

40 2. A machine of the class described having, in combination, an article carrier moving in a predetermined path, transferring mechanism for grasping a moving article and removing it from its carrier, a normally stationary member engaged by the moving carrier as it approaches the transferring mechanism for actuating said mechanism, and means for varying the timing of the actuation of the transferring mechanism with respect to the position of the moving carrier while maintaining the normal stationary position of the member unchanged.

45 3. A machine of the class described having, in combination, an article carrier moving in a predetermined path, transferring mechanism for grasping the moving article and removing it from the carrier, said mechanism comprising grippers, mechanism for actuating the grippers including causing them to come to rest in open position in the path of an approaching article, and means engaged by the article carrier for throwing said actuating mechanism into operation to cause the grippers to close upon the article and remove it from the carrier.

50 4. A machine of the class described having, in combination, article carriers movable in a circular path with the margin of the articles projecting from the carriers, and transferring and stacking mechanism for engaging the projecting margins

5 of the articles, removing the articles from the carriers, stacking them and pressing each article down upon the stack, said mechanism including pressing means and a pair of grippers between the open jaws of which the margins of the articles are carried, and means thrown into operation by the moving carriers to close the grippers on the articles, to move them bodily away from the carrier to open the grippers to deposit the articles on a stack and to press the articles thus 10 delivered upon the stack.

55 5. A machine of the class described having, in combination, article carriers movable in a predetermined path, and mechanism located adjacent to the path of the carriers and actuated successively by the moving carriers as said carriers approach the mechanism for removing the articles from the carriers and stacking them, said mechanism comprising a support for a stack of articles, a pair of grippers movable from 20 receiving position adjacent to the path of movement of the carriers to releasing position above the stack support, yielding means for closing the grippers, a catch for holding the grippers open in their receiving position, and means 25 thrown into operation successively by the carriers for moving the catch to permit the grippers to close, for moving the grippers to releasing position and there opening them and for returning them to receiving position and holding them 30 open.

60 6. Mechanism for taking articles from a carrier and stacking them having, in combination, a stack support, a pair of grippers mounted for movement from receiving position adjacent to 35 the path of the carrier to releasing position above the stack support and back to receiving position, means for engaging and opening the grippers in releasing position, a catch for holding them open as they are returned and brought to rest in receiving position, actuating mechanism for imparting movement to the grippers from receiving position to releasing position and back again, and means engaged and moved by a carrier for disengaging the catch and for rendering the actuating mechanism operative.

65 7. Mechanism for taking articles from a moving carrier and stacking them having, in combination, a stack support, a pair of grippers mounted for movement from receiving position 50 adjacent to the path of the carrier to releasing position above the stack support and back to receiving position, means for engaging and opening the grippers in releasing position, a catch for holding them open as they are returned to and brought to rest in receiving position, a presser operated by the movement of the grippers to receiving position to press the released articles upon the stack on the support, a catch for engaging the presser and holding it in pressing position, 60 actuating mechanism for imparting movement to the grippers from receiving position to releasing position and back again, and means engaged and moved by a carrier for disengaging the catches and for rendering the actuating mechanism operative.

70 8. Mechanism for transferring and stacking articles having, in combination, a stack support, a pair of grippers, means for causing the grippers to grasp an article, to move it into a position 70 above the stack support and there release it, a presser, and means moving with the grippers from their releasing to their grasping position for causing the presser to act upon a released article.

9. A machine of the class described having, in combination, an article carrier moving in a predetermined path, a stack support, mechanism for transferring an article from the carrier into a position above the stack support, mechanism for pressing the articles against the stack support, and actuating means thrown into operation by a moving carrier for operating both said mechanisms.
10. A machine of the class described having, in combination, a plurality of carriers for flat articles of sheet material, said carriers being movable in a circular path which includes the plane of the articles, a stack support located adjacent to said path, mechanism for transferring articles one by one from the carriers into a position above the stack support, mechanism for pressing the articles against the stack support, and actuating means including a clutch thrown into operation by a moving carrier for operating both mechanisms.
11. A machine of the class described having, in combination, an article carrier movable in a predetermined path, transferring mechanism for grasping moving articles and removing them from the carrier, said articles being of such shape that they may be grasped at different localities on them, a normally stationary member engaged by the moving carrier as it approaches the transferring mechanism for actuating said mechanism, means for varying the timing of the actuation of the transferring mechanism with respect to the position of the moving carrier while maintaining the normal stationary position of the member unchanged, and means for varying the locality on the articles which is grasped by the transferring mechanism.

FREDERICK E. HOOPER.
